UNITED STATES PATENT OFFICE.

ALFRED MAUL, OF DRESDEN, GERMANY.

APPARATUS FOR DISCONNECTING MACHINERY.

SPECIFICATION forming part of Letters Patent No. 663,035, dated December 4, 1900.

Application filed January 3, 1900. Serial No. 288. (No model.)

To all whom it may concern:

Be it known that I, ALFRED MAUL, a citizen of the Kingdom of Saxony, residing at Dresden, in the Kingdom of Saxony, in the 5 German Empire, have invented certain new and useful Improvements in Apparatus for Disconnecting Machinery; and I do declare the following to be a full, clear, and exact description of the invention, such as will enable 10 others skilled in the art to which it appertains to make and use the same, reference being had to the accompanying drawings, and to the characters of reference marked thereon, which form a part of this specification.

15 In manufactories and other installations where machinery is used accidents frequently occur and their seriousness is increased by reason of the workman who meets with an accident or his companion near him being unable 20 to stop the prime mover or the machinery, it being first necessary to communicate with the engine-driver, whereby in many cases much time is lost.

This invention has for its object to provide 25 an apparatus by means of which any one may by a slight pressure or pull easily and suddenly disconnect the prime mover from the machinery from a distance, so as to stop the machinery at the place of an accident or where 30 this is seen to be about to occur.

The apparatus is preferably operated by 35 electricity and through suitable connections for releasing a heavily-weighted lever normally held in a slightly-oblique position, in falling from which and with the force thereby obtained it shifts a driving-belt from a fast to a loose pulley or disengages a toothed coupling or the like.

Figure 1 is a side elevation of a mechanism 40 embodying my invention. Fig. 2 is a similar view showing the smaller lever in the act of falling. Fig. 3 is also a side elevation showing the levers in their depressed positions. Fig. 4 is a front elevation. Fig. 5 is a plan view. Figs. 6 and 7 are detail views of the pawl *f*. Figs. 8 and 9 are detail views of the pawl and armature and pivot *k* and its attachments.

a is the heavily-weighted lever, the lower 45 end of which is fixed in a turning pivot *b*, carried in a frame *c*, attached to a wall-plate *c'*, and held in the normal position by means

of a tooth *d* in said pivot engaging with a pawl *f*, mounted on a shaft *e*, Fig. 1, the pawl *f* being held by a spring *g*, which at one end 55 is attached to a set-screw *h* and at the other end to an extension *i* of the pawl. In order to be able with only a slight exertion of force to release the tooth *d*, a smaller weighted lever *l* is provided, which is fixed in a turning 60 pivot *k*, also carried in the frame *c*, and, like the lever *a*, standing at a slight angle to the vertical line. In the pivot *k* is a tooth *m*, engaging against a lug *n* of an electromagnet-armature *o*, which, like the pawl *f*, is held 65 suspended, or so that it may oscillate. The lug *n* is held to the tooth *m* by a spring *p*, Figs. 4 and 5, attached at one end to a set-screw *q*, Fig. 5, and at the other end to an extension of the magnet-armature *o*. 70

In addition to the tooth *m* the pivot *k* is provided with a lug *r*, so placed that upon the turning of this pivot it strikes a projection *s*, Figs. 7 and 8, of the pawl *f* and presses this backward out of reach of the tooth *d*. 75

t represents two magnet-bobbins arranged in front of the armature *o* and interposed in a circuit. The contact places are located in the machinery rooms or workshops, within easy reach of the workmen. These magnet-bobbins serve when energized by the current 80 to attract the armature and so bring it out of reach of the tooth *m*.

With the apparatus in the normal or state-of-rest position of Fig. 1 and a workman, 85 having regard to a prospective or actual accident, desiring to disconnect the engine to stop the transmission of movement therefrom he will at his own or at an adjacent workman's place close the contact, so that the 90 magnet-bobbins receive current, whereupon the operation is as follows: The magnet-bobbins *t* attract the armature *o*, so that the small weighted lever *l* causes the lug *r* of this lever to strike against the projecting part *s* 95 of the pawl *f* and the drawing away of this latter from the tooth *d*, which bears with great force against it, so that now the larger weighted lever *a*, being no longer held, falls to one side, Fig. 4, and by reason of the great 100 force thereby developed brings about the displacement of the driving-band of the prime mover from a fast to a loose pulley or the disconnection of a toothed coupling or the like.

To this end there is fixed on the turning pivot *b* of the large weighted lever *a* and further connected with this latter by a bolt *u* a grooved wheel-segment *v*, to which a wire rope *w* is attached, and thence led and attached to a sliding fork for displacing the driving-band or to a lever for disconnecting the coupling or the like, which parts are correspondingly moved when the weighted lever *a* falls.

x y z are set-screws located in the frame *c* for the large and small weighted levers, by which these latter, the magnet-armature, and the pawl are set to correspond to the before-described action, the screw *x* preventing the spring *p* from drawing the armature too far back and away from the influence of the magnet-bobbins, the screw *y* preventing the spring *g* from pulling the pawl *f* too far over the stop-tooth *d*, and the screw *z* preventing the lever *a* from taking a too-upright position and so that this lever will when released always fall to one side.

In order to be able to regulate the force of the falling levers *a l*, these are provided, respectively, with weights *a' l'*, adjustable by set-screws 1 2.

When the apparatus after being actuated is in the position of Fig. 3, it can be again brought into a position for further use by raising and locking in the described manner first the small weighted lever *l* and then the larger lever *a*.

In the described arrangement and action of the apparatus it is supposed that the magnet-bobbins are traversed by a so-called "working" current only when the contacts are closed; but instead of such a current a continuous current may be employed, in which case the normally-attracted armature *o* can be located on the left side of the magnet-bobbins. Only then the lug *n* must be made sufficiently long to come within the reach of the tooth *m*, it also being necessary to provide a spring which upon the break of circuit would withdraw the armature *o* with its lug *n* from the tooth *m*.

In the above or equivalent construction of the apparatus the release of the weighted lever may, instead of electrically, be accomplished by other means—such, for instance, as by a pull on a rope.

What I claim, and desire to secure by Letters Patent, is—

1. In a mechanism such as described, a larger weighted lever, a turning pivot to which the lever is secured, and which is provided with a tooth, combined with the pivoted pawl with which the tooth engages, and an electromagnet and its armature, a shorter weighted lever, a pivot to which the shorter lever is connected, and which is also provided with a tooth to engage with the armature, and a projection for engaging with the pawl, whereby when the smaller lever falls, the larger lever is tripped, substantially as shown.

2. In a mechanism such as described, a longer weighted lever, the pivot to which the lever is connected and which is provided with a tooth for engaging with the pawl, a pivoted pawl, an electromagnet and its armature, combined with a second shorter weighted lever, a pivot to which it is connected and which is provided with a tooth for engaging with the armature, and a projection for engaging with the pawl, and a segment connected to the pivot to which the longer weighted lever is secured, substantially as described.

3. In a mechanism such as described, the longer weighted lever, the turning pivot to which it is secured, the segment secured to the pivot, the tooth *d* also secured to the pivot, the pawl *f* which engages the tooth upon the pivot and has a projection *s*, an electromagnet, and its armature provided with a lug upon its lower end, combined with a shorter pivoted and weighted lever, the pivot to which it is secured and which is provided with a tooth *m*, which engages with the lug upon the armature, a spring connected to the upper end of the pawl so as to force its lower end toward the pivot *b*, and the projection *r* secured to the pivot of the shorter lever for striking against the projection on the pawl, and the regulating set-screws for limiting the movement of the levers, substantially as set forth.

In testimony whereof I affix my signature in presence of two witnesses.

ALFRED MAUL.
